UNITED STATES PATENT OFFICE

2,277,949

CENTRIFUGAL SEPARATOR

Wilmer Hiestand Bath, West Conshohocken, Pa.,
assignor to The Sharples Corporation, Philadelphia, Pa., a corporation of Delaware

Application November 19, 1940, Serial No. 366,217

6 Claims. (Cl. 233—21)

The present invention pertains to the art of centrifugal separators of the type adapted to separate a solid from a liquid or liquids from each other in a centrifugal rotor during continuous feed to that rotor of a mixture to be subjected to the centrifugal separating operation. In particular, the invention pertains to the provision of means for sealing the rotor against entry or escape of gases or vapors during the separating operation, and for automatically permitting drainage of liquid away from the machine when the operation of the rotor is stopped.

In my prior patent, 1,750,154, I have illustrated a drag mechanism and bearing arrangement for the lower end of a centrifugal separator of the tubular type, the liquid to be treated being fed into the centrifugal rotor through registering openings in the bottom of the centrifugal frame and the bottom of the centrifugal rotor. Liquid leakage does not occur from the bottom of this centrifugal rotor during the normal feed of liquid to the rotor and rotation of the rotor. In case some obstruction occurs in the rotor, however, and in any case at the termination of the rotation of the rotor in the treatment of liquid, liquid drains from the main body of the centrifugal rotor through the discharge outlet 50 illustrated in Figure 1 of the patent drawing.

While the provision of a constantly open drainage outlet in the lower part of the frame constitutes a satisfactory arrangement for permitting drainage in treatment of many substances, there are certain substances which cannot be satisfactorily treated in a machine provided with such an open drainage feature. In the treatment of certain substances, such as lacquers for example, the admission of air into the centrifugal rotor is undesirable because of changes which may be effected by contact of the air with the liquid under treatment. When a drainage outlet such as that illustrated in my prior patent is provided, air is sucked into the centrifugal rotor through the drainage space during the normal operation of the machine on the liquid under treatment, and it is desirable in many cases to prevent this from occurring. In the treatment of certain substances, it is also frequently undesirable that vapors of the material under treatment be permitted to escape to the outside atmosphere, and it is frequently desirable for this reason that no opening be provided which communicates through the base of the centrifugal frame directly with the outside atmosphere.

One method of solving the difficulties encountered in treatment of liquids presenting problems

of the type discussed above has been to provide a discharge conduit in place of the outlet 50 of my prior patent, and to provide a valve in this discharge conduit which prevents escape of vapor or ingress of air, except at times at which the operator may deliberately open the valve for the purpose of allowing liquid to discharge from the centrifugal rotor and frame.

This expedient has constituted only a partial solution of the difficulty, however. In the first place, in case some obstruction occurs in the centrifugal rotor which causes unexpected leakage of liquid through the base of the rotor, the provision of a manually operated valve does not constitute a solution of the problem, since the operator does not know when to expect this kind of difficulty, and cannot therefore make provision for it by operation of the valve at the appropriate time. As a consequence of this fact, leakage into the main body of the centrifugal frame may occur, with a consequent possibility of damage to the parts of the drag mechanism, in spite of provision of a manually operated valve. A second objection to the provision of a manually operated valve lies in the fact that the operator may forget to open such a valve at the proper time, and that flooding of the drag mechanism by liquid draining from the rotor may occur as the result of such neglect.

The object of the present invention has been to provide a centrifugal rotor having automatically operable means for preventing ingress of air or escape of vapors during the normal operation of the machine, such means being automatically opened upon drainage of liquid from the centrifugal rotor to permit the drainage liquid to escape from the machine.

A further object of the invention has been to control the operation of the centrifugal, so as to stop the centrifugal rotor, cut off feed of liquid to the centrifugal, or otherwise interrupt the normal operation of the machine in case leakage occurs from the bottom of the centrifugal rotor.

Further objects and advantages of the invention and the manner in which they have been obtained will be evident from a reading of the following detailed description in the light of the attached drawing, in which,

Figure 1 is a cross sectional view of the lower part of a centrifugal rotor, frame, and feeding and bearing connections for the lower end of the centrifugal rotor.

Figure 2 is an enlarged cross section of the apparatus constituting the feature of the invention, and

Figure 3 is a detailed side elevation of the automatic valve of the present invention, showing this valve in open position.

Referring to the drawing by reference characters, the rotor 10 of the centrifugal machine may be of the conventional tubular design illustrated in my prior Patent 1,750,154. This rotor is mounted in a centrifugal frame 11 and is driven by suitable pulley and spindle or other driving connections secured to the upper end of the rotor, as will be evident from inspection of Figure 1 of the drawing of my prior patent referred to above.

Liquid is fed to the centrifugal rotor through a feed conduit 12 secured to a plug 13 in the lower end of the centrifugal frame 11. A nozzle 14 is secured centrally within the plug 13 and is aligned with the upper end of the feed conduit 12 in order that liquid fed through the conduit 12 may be injected through the upper end of the nozzle 14 into the hollow interior of the boss 15 secured to the lower end of the rotor. The boss 15 is secured centrally within a drag (flexible bearing mounting) mechanism 16 of the same general type as that covered by my Patent 1,750,154, referred to above.

The hollow interior 18 of the plug 13 is connected, at its lower end, to a discharge tube 17 which may be removably secured within a lateral opening in the plug 13 by means of a pin and slot connection 22. The hollow interior of the plug 13 forms, together with the discharge tube 17, a conduit for directing the flow of liquid away from the lower end of the boss 15 on the bottom of the rotor, upon drainage of liquid from the rotor.

A disc or valve 19 is removably secured to the lower end of the discharge tube 17. The disc or valve 19 is adapted to be retained in closed position during the feed of liquid to the rotor 10 and the rotation of that rotor, but is adapted to be automatically opened upon stopping of the rotation of the rotor and drainage of the liquid into the tube 17. In order to accomplish closure of the connection between the upper side of the disc or valve 19 and the under side of the discharge tube 17, the disc or valve 19 is pivotally secured to a fixed part of the apparatus, such as the exterior of the discharge tube 17, as illustrated by the pivotal connection 20 of the drawing. The arm 23 which carries the disc or valve 19 and is pivoted at 20 carries a counter-weight 21 which is adapted normally to urge the disc or valve 19 with a relatively light force against the under side of the discharge tube 17.

The apparatus consisting of the disc or valve 19, the arm 23, and the counter-weight 21 is operatively connected to the motor which drives the pump for feeding liquid to the machine to be treated, to the motor which drives the centrifugal rotor, or to both of these motors, in such a way as to interrupt the feed of liquid to the machine and/or to interrupt the rotation of the centrifugal rotor, upon opening of the valve 19 during the normal operation of the machine. This may be accomplished by providing a switch 24 carried by one of the parts which moves with the valve 19 (the counter-weight 21, as illustrated), and arranging this switch in an electric circuit which includes a conductor 25 through which electrical energy is received, and conductors 26 and 26' connecting switch 24 with motors 27 and 27' for driving the feed pump and centrifugal rotor, respectively.

The operation of the machine, and the manner in which the objects of the invention are at- 75

tained in that operation will now be apparent. In the normal operation of the machine, the fluid mixture to be subjected to centrifugation is passed through conduit 12 and nozzle 14 into the lower end of the centrifugal rotor 10, and the centrifuged liquid from within the rotor 10 is continuously discharged from a suitable weir or weirs during the continuous rotation of the rotor. During this normal operation of the machine, the disc or valve 19 is maintained in sealing relationship against its seat on the lower end of the discharge tube 17, the natural suction effect caused by discharge of liquid from the nozzle 14 into the boss 15 of the centrifugal rotor serving to reinforce the effect of the counter-weight 21 and maintain the disc or valve 19 in fairly firm sealing relationship against the tube 17.

When the operator desires to discontinue the operation of centrifugation, he cuts off the feed of liquid through the conduit 12 and stops the rotor 10. Upon stopping of the rotation of the rotor 10, the liquid still remaining in that rotor will flow downwardly through the interior of the boss 15 into the chamber 18 in the interior of the plug 13, and from the chamber 18 into the discharge tube 17. At this time, the suction effect tending to pull the disc or valve 19 upwardly has been discontinued by discontinuance of feed of liquid through the nozzle 14, and the disc or valve is accordingly held in closing position only by the force exerted by the counter-weight 21. As soon as liquid has drained through the tube 17 to a sufficient extent to form a substantial layer of liquid in the lower end of the tube 17 above the disc or valve 19, the weight of this liquid will overcome the closing force exerted by the counter-weight 21 and force the disc or valve 19 to move to open position, as illustrated in Figure 3 of the drawing. This permits drainage of the liquid from the tube 17. After drainage of liquid from the tube 17 has been completed, the disc or valve 19 will again be swung to the closing position illustrated in Figure 2 of the drawing by the effect of the counter-weight 21, and the normal operation of the machine may then be resumed.

If, during the normal operation of the machine, some accident occurs, such as an obstruction in passage of liquid through the centrifugal rotor, with the result that liquid is discharged downwardly from the rotor into the chamber 18, the apparatus of the invention will function automatically in much the same manner as that described above with respect to the operation occurring when the rotor is stopped. Thus, if a substantial quantity of liquid leaks into the space 18 during the normal feed of liquid to the rotor and rotation of liquid in the rotor, this liquid will pass downwardly through discharge tube 17 and accumulate above the disc or valve 19. After accumulation of liquid above the disc 19 to a predetermined depth, this disc will be forced into open position against the effect of the counter-weight 21, as illustrated in Figure 3 of the drawing. At the same time, the electrical connection controlled by the switch 24 in the circuit 25 will be broken, with the result that the feed of liquid to the centrifugal will be stopped, and the rotation of the centrifugal rotor also stops, if desired. It will be seen that the invention thus provides an arrangement by which the normal operation of the machine will be automatically stopped in case something goes wrong with the functioning of the machine to effect discharge of liquid through the normal outlets for the liquid.

Modifications will be obvious to those skilled in the art, and I do not therefore wish to be limited except by the scope of the following claims.

I claim:

1. In a centrifugal separator, the combination comprising, a centrifugal rotor, means for feeding liquid to said rotor during rotation thereof, a frame surrounding the bottom portion of said rotor and provided with a discharge outlet for liquid drained from the rotor, a valve associated with said outlet and controlling discharge of liquid therefrom, means associated with said valve for holding it normally in closed position during discharge of liquid until said liquid reaches a predetermined depth above said valve, and means responsive to accumulation of a predetermined quantity of liquid above said valve for actuating said valve to open position.

2. In a centrifugal separator, the combination comprising, a centrifugal rotor, means for feeding liquid to the bottom of said rotor during rotation thereof, a frame surrounding the bottom portion of said rotor and provided with a discharge outlet for liquid drained from the rotor, a valve associated with said outlet and controlling discharge of liquid therefrom, means associated with said valve for holding it normally in closed position during discharge of liquid until said liquid reaches a predetermined depth above said valve, and means responsive to accumulation of a predetermined quantity of liquid above said valve for actuating said valve to open position.

3. In a centrifugal separator, the combination comprising, a centrifugal rotor, means for feeding liquid to said rotor during rotation thereof, a frame surrounding the bottom portion of said rotor and provided with a discharge outlet for liquid drained from the rotor, a valve associated with said outlet and controlling discharge of liquid therefrom, means associated with said valve for holding it normally in closed position during discharge of liquid until said liquid reaches a predetermined depth above said valve, means responsive to accumulation of a predetermined quantity of liquid above said valve for actuating said valve to open position, and means controlled by actuation of said valve to open po-

sition for discontinuing feed of liquid to said rotor.

4. In a centrifugal separator, the combination comprising, a centrifugal rotor, means for feeding liquid to said rotor during rotation thereof, a frame surrounding the bottom portion of said rotor and provided with a discharge outlet for liquid drained from the rotor, a valve associated with said outlet and controlling discharge of liquid therefrom, means associated with said valve for holding it normally in closed position during discharge of liquid until said liquid reaches a predetermined depth above said valve, means responsive to accumulation of a predetermined quantity of liquid above said valve for actuating said valve to open position, and means controlled by actuation of said valve to open position for interrupting the driving of said rotor.

5. In a centrifugal separator, the combination comprising, a centrifugal rotor, means for feeding liquid to said rotor during rotation thereof, a frame surrounding the pump portion of said rotor and provided with a discharge outlet for liquid drained from the rotor, a disc normally contacting said drainage outlet to seal said frame from entry of vapors or discharge of liquid, means associated with said disc for normally holding it in closed position against said outlet during discharge of liquid until said liquid reaches a predetermined depth above said disc, and means responsive to accumulation of a predetermined quantity of liquid above said disc for actuating said disc to open position.

6. In a centrifugal separator, the combination comprising, a centrifugal rotor, means for feeding liquid to said rotor during rotation thereof, a frame surrounding the pump portion of said rotor and provided with a discharge outlet for liquid drained from the rotor, a disc normally contacting said drainage outlet to seal said frame from entry of vapors or discharge of liquid, a counter-weight associated with said disc for normally holding it in closed position against said outlet during discharge of liquid until said liquid reaches a predetermined depth above said disc, and means responsive to accumulation of a predetermined quantity of liquid above said disc for actuating said disc to open position.

WILMER Hiestand Bath.
